UNITED STATES PATENT OFFICE.

JOHN A. GOGOLINSKI, OF DRISSA, RUSSIA.

PUMP.

1,349,667.

Specification of Letters Patent. Patented Aug. 17, 1920.

Application filed May 24, 1918. Serial No. 236,292.

To all whom it may concern:

Be it known that I, JOHN A. GOGOLINSKI, a subject of Russian Poland, residing at Drissa, in the District of Vitebsk, Russia, have invented a new and useful Improvement in Pumps, of which the following is a specification.

The object of this invention is to provide an improved pump suitable for circulating the lubricating oil in an engine of any type, inclusive of the internal combustion type.

The accompanying drawings show two forms of embodiments of the invention.

Figures 1, 2, 3 and 4 show, in different positions, a single unit containing the invention.

Fig. 5 shows a vertical section of the invention applied to a plurality of pumps operated as a unit.

Fig. 6 shows a section of the same on the line 6—6 of Fig. 5.

Fig. 7, 8, 9 and 10 are details of the same.

Referring to Figs. 1, 2, 3 and 4, p and p' are portions of a casing containing the inlet ports a , a' , and outlet ports b , b' . e , e' are pump cylinders in alignment with each other provided with the laterally extending flanges e^2 , e^3 . e is a rigid rod carrying the pistons e' , e^2 and provided with an eye e^3 in which the crank pin d' of the crank d operates. The heads of the cylinders are provided with the openings c^4 and c^5 which have a valve coöperation respectively with the ports a , b and a' , b' , as the cylinders are slid laterally by the movement of the crank d on the opposed surfaces of the casing p , p' .

In Fig. 1, the crank is shown on its dead center in line with the axis of the cylinders, the ports being closed and the cylinder e charged with oil. A movement of the crank 40 90° in the direction of the arrow, as shown in Fig. 2, shifts the cylinders e , e' to the left of the axis of the shaft, opening outlet port b to cylinder e , and inlet port a' to cylinder e' . A further movement of 90° in the same direction, closes all ports and charges the cylinder e' with oil, as shown in Fig. 3.

A further 90° movement of the crank shifts the cylinders to the right of the axis of the shaft, opening cylinder e to inlet a and cylinder e' to outlet b' .

Figs. 5 and 6 show a plurality of the above described pumps operated as a unit. P is a casing to which a cover f is hermetically fixed, forming a reservoir into which oil is fed through the opening g (Fig. 7). The inner faces of the casing walls p , p' are fin-

ished to receive two sliding blocks l , l' , shown partly in section in Fig. 5. The cover f is provided with a central opening forming a bearing for the hub h' of the pinion h , rotating within the reservoir and which is actuated by a worm i on the shaft i' journaled in the cover f (Fig. 7). The hub of pinion h is provided with an eccentric pin j' on one side, and a concentric stud j^2 on the opposite side. The stud j^2 extends through the wall of the hub and carries on the outside a knurled knob k fixed to it, and secured by a nut k' . A coiled spring k^2 is interposed between the disk j and the wall of the hub. The eccentric j' enters an opening in the bar m , to which are fixed a number of rods or pistons n extending an equal distance on both sides of the bar, and adapted to coöperate with cylinder bores in the blocks l and l' .

As seen in Figs. 5, 6 and 7, the rotation of the pinion h causes pin j' to reciprocate bar m which actuates the blocks l and l' producing movement of the pistons n in their cylinders. At the same time it slides the blocks l and l' on the casing p and p' , and causes a valve coöperation between the openings in the heads of the cylinders and the inlet and outlet ports a , a' and b , b' , similar to that described for Figs. 1, 2, 3 and 4.

Springs s and s' set in recesses in blocks l and l' maintain the same in frictional contact with the faces of the casing walls. The base of the knob k is provided on its periphery with a number of recesses r coöperating with the pin o . When the knob k is lifted out of engagement with the pin o , it may be turned and seated again at the desired adjustment where it will be held under the tension of the spring k^2 . By this adjustment of the eccentric pin j' , the stroke of the piston n may be increased or diminished, and the quantity of pressed oil increased or diminished during each cycle. Thus full regulation of the quantity of the expulsed oil from zero to the maximum is obtainable.

In Figs. 5 and 6, twenty cylinders in all are indicated, ten with their axes in one plane, and ten with their axes in a plane parallel therewith. Each block l and l' contains ten cylinders.

It will be observed that in the above illustrations of my invention, the pistons of opposite cylinders are coupled rigidly together by the interposed rods, and are operated from a single regulated crank by a turning

eccentric; both the piston action and the valve action being transmitted from the crank or eccentric through the rod connecting the opposed pistons. It will also be seen 5 that in the construction shown in Figs. 5, 6 and 7, the casing which is designed to contain the pumps, the driving and other mechanisms, is also part of a reservoir from which the oil which surrounds the pumps 10 etc. may be distributed through pipes connecting with the respective pumps.

I have above described the form in which I prefer to embody my invention at the present time, but said form is susceptible of 15 wide variation without departing from the principle of my invention.

What I claim and desire to secure by Letters Patent of the United States, is:—

1. In a pump, in combination, two stationary parts containing inlet and outlet ports, 20 two inversely arranged cylinders sliding upon said parts and containing openings to coöperate with said ports, pistons within said cylinders connected by a rod, and means 25 acting on said rod whereby longitudinal and lateral movement is given to the pistons, and lateral movement to the cylinders.

2. In a pump, in combination, two inversely arranged cylinders in axial alinement, 30 parts containing inlet and outlet openings upon which said cylinders are slidably mounted, pistons within said cylinders and means whereby longitudinal and lateral movement is given to the pistons, and lateral 35 movement to the cylinders.

3. In a pump, in combination, a series of 30 slidably mounted cylinders, another slidably mounted series arranged inversely and in axial alinement with the first series, pistons 40 within said cylinders, rods connecting said pistons, a cross member connected with said rods, means imparting to said rods both longitudinal and lateral movement whereby the pistons are moved longitudinally and the 45 cylinders laterally, and the casing contain-

ing inlet and outlet ports coöperating with openings in said cylinders.

4. In a pump, in combination, a casing, a reservoir inclosing parts of the pump, inlet ports connected therewith, and outlet ports, 50 inversely arranged cylinders slidably mounted in said casing and having openings coöperating with said ports, pistons within said cylinders, a rod connecting said pistons, and means whereby said rod is given 55 a longitudinal movement to operate the pistons in the cylinders, and a lateral movement to slide the cylinders on said casing.

5. In a pump, in combination, parts facing each other provided with inlet and outlet 60 ports, a block slidably mounted on each of said parts, a plurality of cylinders formed in each of said blocks, those in one block alined with those in the other, pistons within said cylinders, a rod connecting each piston with its opposite and means whereby 65 said rods are moved longitudinally and laterally.

6. In a pump, in combination, a series of 70 slidably mounted cylinders, another slidably mounted series arranged inversely and in axial alinement with the first series and pistons within said cylinders, rods connecting said pistons, a cross member connected with said rods, and means imparting to said rod 75 both longitudinal and lateral movement whereby the pistons are moved longitudinally and the cylinders laterally, the casing containing inlet and outlet ports coöperating with openings in said cylinders and 80 means for regulating the stroke of the pistons and the quantity of oil expulsed.

In testimony whereof I have hereunto signed my name in the presence of two subscribing witnesses.

JOHN A. GOGOLINSKI.
